CONTAINER FILLING MACHINE

James Kantor, Chicago, Ill., assignor to The Liquid Carbonic Corporation, Chicago, Ill., a corporation of Delaware

Application November 10, 1941, Serial No. 418,459

2 Claims. (Cl. 226—115)

The present invention relates to improvements in container filling apparatus and particularly to apparatus for filling containers with carbonated beverage.

It has for one of its objects that of providing a "two-stage" filler. In the handling of carbonated beverages, in some instances, I have found that the carbonated beverage can be delivered to the container during what may be called the first stage at a comparatively slow rate of flow. As soon as the level of the carbonated beverage delivered to the container has reached to or above the lower end of the filling tube, the rate of flow may be increased to a relatively fast rate without causing unnecessary foaming and I have further found that if the filler valve is closed at the right moment or just before the container is completely filled, there is, under normal circumstances, no danger of the carbonated beverage backing up in the filler valve. It is one of the objects of my invention to provide a machine for accomplishing the above results.

For the purpose of disclosing the invention, I have illustrated an embodiment thereof in the accompanying drawings, in which:

Fig. 1 is an elevation, more or less diagrammatic, of an apparatus embodying my invention;

Fig. 2 is a longitudinal sectional view in detail of the upper part of the water check tank;

Fig. 3 is a plan view, partly in section, showing the conducting ports in the head of the water check tank;

Fig. 4 is a plan view, more or less diagrammatic, showing the control valve arrangement for delivering pressure from the water check tank to the filler tubes; and

Fig. 5 is a longitudinal sectional view of the type of filler tube embodied in my invention looking at the structure from its side, as compared with its end, as shown in Fig. 1.

In the embodiment of the invention illustrated, I provide a filling tank 1 which is annular or doughnut shaped and is provided with a plurality of filling valves 2. This tank, and its associated filling valves, is rotatable and associated with each filling valve and rotatable therewith is a reciprocating platform 3 which, during its reciprocation, moves the container adapted to be received thereon into and out of engagement with its filling valve 2.

Each of the filling valves 2 comprises a base 4 adapted to be secured in a position coincident with an opening in the bottom of the tank 1. This base supports a filler tube 5 adapted to communicate with the interior of the tank and

adapted to be projected into the container to be filled as the container is raised on its support 3. This tube carries, at its lower end, a pear-shaped valve 6 normally adapted to close the lower end of the tube and operated through the medium of a stem 7 which extends upwardly and is connected with a diaphragm 8 mounted in a chamber 9 formed between a cap 10 and a top casting 11. A plurality of pressure tubes 13, preferably two in number, extend upwardly from the base 4, being seated in bosses in the base and corresponding bosses in the top 11. These tubes communicate through passages 14 with the chamber 9 above the diaphragm 8. At the lower ends, the tubes 13 communicate through passages 15 in the base 4 with a chamber 16 in the neck 17 of the filler valve. The neck 17 carries a secondary tube 18 which telescopes the tube 5 and this tube 18, at its upper end, is provided with a valve seat 19 on which is adapted to seat a spring-pressed valve 20. The lower end of the tube 18 projects through a cushioning seat 21, the purpose of which will more fully hereinafter appear.

Slidably mounted on the filler tube 5 is a bottle bell provided with a bell-shaped mouth 22 and having arranged therein a sealing bushing 22'. The upper end 23 of this bell is adapted to make sealing engagement, when the bell is raised, with the sealing gasket or seat 21, while the end of the tube 18 makes contact with the top of the bell to deliver pressure through the bell into the container. This pressure is supplied, in a manner hereinafter more fully described, through a port 24 formed in a nipple 25 adapted to be connected with a suitable pipe or conduit 26.

Counter-pressure to the container to be filled and pressure for operating the valve 6 of the filler tube 5 is supplied to the filler tube through the conduit 26 from a water check tank 27 which rotates with the tank 1 and is provided with a pressure cylinder 28. The tank 27 is provided with means for delivering water thereto through an opening 29 in the bottom of the tank and the tank is closed by a suitable cover 30 which also provides one member of a control valve. The pressure tank 28 is supported within the tank 27 from an air supply tube 31 extending through the head 30 and a boss in the head 33 of the pressure tank receiving clamping units 32 on its end.

This pressure tank or cylinder 28 is open at its bottom and air under pressure is delivered thereto from a suitable source of supply through the pipe 31. The head 33, cooperating with the valve portion of the head 30 provides a valve for controlling the admission of pressure through the

tubes 26 and to this end, the cylinder 28, with its accompanying head 33 is held against rotation by the air supply pipe 31 which, in turn is provided with an adjustable locking member 34 connected to a holding stem 35. For maintaining a tight sliding contact between the head 33 and the head 30, the air supply pipe 31 is provided with a stop 36 and the head 30 is provided with a friction bearing 37 between which is disposed a coiled spring.

In order to equalize the pressure in the top of the water check tank with the pressure above the liquid in the filling tank 1, the filling tank above the liquid level is adapted to be connected with the top of the water check tank 27 through suitable pipes or conduits 38.

In addition to supplying air to the cylinder 28, air is supplied to the top of the water check tank 27 from the air supply pipe 31 through the medium of a passageway 39 in the head 33, which extends to the outer periphery of the head and communicates with the pipe 31.

The head 30 of the water check tank is provided with a plurality of radial passageways 40, one for each of the tubes 26, which radial passageways communicate with vertically disposed ports 41. The head 33, on its upper face has formed therein a segmental annular groove 42 and a second segmental annular groove 43. The annular groove 42 communicates with the top of the water check tank through the medium of suitable ports 44, and the annular groove 43 communicates with the cylinder 28 through suitable ports 45 in the head so that when the groove 42, due to the relative rotation between the head 33 and the head 30, is placed in communication with the ports 41, each of the tubes 26 will be placed in communication with the top of the water check tank 27 and when the groove 43 is placed in communication with the ports 41, each of the tubes 26 is placed in communication with the pressure cylinder 28.

Air under pressure is admitted to the cylinder 28 through the tube 31 sufficient to force out of the open bottom of this cylinder water which would tend to rise therein from the water check tank. There is developed in the cylinder 28 a pressure sufficient to support a column of water extending from the water level in the water check tank to the bottom of the cylinder 28. This column may be indicated as A. With the tube 28 placed in communication with the container to be filled through the filling valve, there will be developed in the container a similar pressure which, of course, will support a column of liquid similar in height, and this column from the liquid level in the tank to the bottom thereof may be designated as A' and it will be noted that this column extends from the liquid level in the tank to just above the bottom end of the filling tube when it is projected into the bottle. Therefore, there will be a differential in pressures between the pressure tending to flow the liquid from the filling tank into the bottle and the pressure tending to prevent this flow equal to the difference between the distance A' and the end of the filling tube 5, which may be designated as B, and B will be the effective head tending to flow the liquid into the bottle. Obviously, when the liquid reaches a point equal to the distance B, the pressures will be counterbalanced and no more liquid would tend to flow into the bottle until a further differential is provided.

In operation, assuming that the filler tank and water check tank, together with the associated

filling valves and container supports are rotating, with the cylinder 28 remaining stationary, as a bottle is received on its support 3, this support is raised, raising the bottle with it into engagement with the bell mouth 21, thus raising the bell member until the top 23 of this member seats on the gasket 21. This, of course, makes a sealed engagement between the parts so that the bottle will be placed in communication with the filling valve. At the same time that the top 23 of the bell member seats on the rubber seat 21, the lower end of the tube 18 seats itself and the valve 20 is raised, placing the tube in communication with the chamber 16 thus admitting pressure from the conduit 26 to the bottle to be filled and, likewise, to the chamber 9 above the diaphragm 8, which will develop sufficient pressure above the diaphragm 8 to move the stem 7 downwardly, opening the valve 6. It is, of course, to be understood that upon rotation of the filler tank and water check tank, the port 41 will be placed in communication with the groove 43 and thus through the port 45 with the interior of the cylinder 28. Under these circumstances, it is obvious that the counter-pressure developed in the container to be filled will be sufficient to allow the liquid in the filler tank 1 to flow into the container at a comparatively slow speed and that when the liquid is filled to a level in the bottle which would equal column B, the flow in the liquid into the container will stop. However, before this level is reached and shortly after the end of the filling tube 5 is submerged, the port 41 will have been placed into communication with the groove 42 which, it will be remembered, communicates directly with the top of the water check tank 27 and, therefore, the counter-pressure admitted to the container will be equal to the pressure in the top of the tank 1 so that the full head or weight of the liquid in the tank 1 will cause the liquid to flow through the filling tube and, under these circumstances, the liquid will flow at a relatively much higher rate. Under this arrangement, there is no counter-pressure developed sufficient to stop the flow of liquid when the container is filled and, as a result, there would be a tendency for the liquid to creep up in the filling valve to a point considerably above the liquid level to which it is desired to fill the bottle. To avoid any such contingency, the apparatus is operated at such a speed, and the cam mechanism for raising and lowering the bottles is so timed that at the point where the desired liquid level is reached in the bottle, the platform or support 3 commences to lower, thus closing the valve 20, shutting off the supply of pressure to the chamber 9 and under these circumstances, permitting the valve 6 to close, shutting off the flow of liquid to the tube 5. In other words, the closure of the valve 2 is timed to coincide with the point at which it is desired that the liquid level shall be reached in the container.

I claim as my invention:

1. In a container filling machine, in combination, a rotary filling tank adapted to be supplied with liquid to be delivered to the container, a filling valve associated with said tank including a filling tube for projection into the container to be filled and having a discharge opening at its lower end and a valve for controlling the discharge of liquid from the lower end of said tube, said filler valve having a pressure inlet passage for delivering counter-pressure to the container, a water check tank having an air cylinder therein communicating at its bottom with said water check

tank, means for admitting air under pressure to said cylinder to develop pressure in said cylinder against the water contained in said water check tank, means for admitting said air pressure in said water check tank above the water contained therein and a valve rotated with said tank and having control ports respectively connected to said air cylinder and said tank and initially connecting said filler valve with said cylinder through one port to develop counter-pressure from said cylinder to said container, said valve, after a predetermined quantity of liquid has been delivered to the container, connecting the filler valve through the other port with the top of said water check tank to equalize the pressure in said container with the pressure in the top of the filler tank and said filler tube and means for closing said valve to shut off the supply of liquid to the container coincident with the rise of the liquid level in said container to the desired point above the discharge end of the tube.

2. In a container filling machine, in combination, a rotary filling tank adapted to be supplied with liquid to be delivered to the container, a filling valve associated with said tank including a filling tube for projection into the container to be filled and having a discharge opening at its lower end and a valve for controlling the discharge of liquid from the lower end of said filling tube, said filling valve having a pressure inlet passage for delivering counter-pressure to the

5 container, a water check tank having an air-cylinder therein communicating at its bottom with said water check tank, means for admitting air under pressure to said cylinder to develop pressure in said cylinder against the water contained in said water check tank, and means for admitting air pressure in said water check tank above the water contained therein, a valve rotated with said tank having control ports respectively connected to said air cylinder and said tank and initially connecting said filler valve with said cylinder through one of said ports to deliver counter-pressure to said container, the counter-pressure so delivered to said container having a differential less than the head of liquid in said filler tank sufficient to permit the liquid to discharge from said filler tank into the container to a level approximately at the discharge end of said filling tube, said valve, after the liquid in the container reaches the above-mentioned level, connecting the filler valve with the top of the water check tank through said other valve to equalize the pressure in the container with the pressure in the top of the filler tank and said filling tube valve, means for closing said filling tube valve to shut off the supply of liquid to the container coincident with the rise of the liquid level in the container to the desired point above the discharge end of the tube.

JAMES KANTOR.
